UNITED STATES PATENT OFFICE.

EDWIN E. SLICK, OF PITTSBURG, PENNSYLVANIA.

RAIL-FASTENING.

950,080.

Specification of Letters Patent. Patented Feb. 22, 1910.

Application filed February 28, 1907. Serial No. 359,862.

To all whom it may concern:

Be it known that I, EDWIN E. SLICK, of Pittsburgh, Allegheny county, Pennsylvania, have invented a new and useful Rail-Fastening, of which the following is a full, clear, and exact description, reference being had to the accompanying drawings, forming part of this specification, in which—

Figure 1 is a top plan view showing my improved fastening in position; Fig. 2 is a cross-section of the rail, showing the fastening in position; Fig. 3 is a partial cross-section of the steel tie, provided with the fastening; and Fig. 4 is a plan view showing the method of rolling and severing the tie plates.

My invention relates to the securing of rails to ties, and particularly to steel or iron ties.

20 The object of the invention is to provide a fastening by which the rail may be secured without the use of bolts or rivets which must be adjusted or removed in removing or replacing the rail and fastening.

25 A further object of the invention is to provide an iron or steel tie with a fastening device which may be permanently secured thereto at the point of manufacture, while the rail may be held thereby without the use 30 of any securing bolts or rivets which are applied when the rail is put in place.

A further object is to provide a quick and easy means for adjusting the rail sidewise.

To that end, the invention consists in securing clips or flanges which extend at an angle to the rail and are spaced a sufficient distance apart to allow the rail to be inserted without endwise threading thereof; and also in providing wedge-sections which shall be 40 inserted in both sides of the rail base to secure the rail in place.

A further object is to provide a tie plate having securing flanges, which plates may be rolled in multiple lengths and the plates 45 sheared or otherwise cut therefrom at an angle other than a right angle, thus enabling oppositely-driven wedges to be used in fastening the rail.

In the drawings, referring to Fig. 4, I 50 show the preferred form of making my improved tie-plate. In its manufacture I roll a length or blank 2, having parallel flanges 3, 3 projecting from one face thereof and

arranged preferably inside of the side edges of the blank. The blank is then severed 55 transversely on the dotted lines, thus giving the improved tie-plate. In using these plates with metal ties, they are preferably riveted to the ties at the place of manufacture, as shown in Figs. 1, 2 and 3, wherein 4 are the 60 securing rivets extending through the plates through a layer of insulation shown at 5, and through the top flanges 6, 6, of the I-beam form of tie here shown. These rivets may be provided with insulating thimbles 65 to insulate the rail and plate from the tie. The width of the space between the tie-plate flanges is such that the rail may be dropped into place from above and preferably wide enough so that it may be so inserted without 70 swinging the rail or tie to a position other than its final one. When the rail is dropped into place, the wedge-shaped keys 7 are driven in between the tie-plate flanges and the rail-base, these being inserted from opposite sides. By loosening one key and driving in the other the rail may be adjusted 75 sidewise as desired; and to secure the wedges in place I then preferably bend down their smaller projecting ends on the opposite sides 80 of the tie-plate, as shown in Fig. 3. These keys are preferably recessed on their inner edges to lap over or fit upon the base flanges of the rail, and are made of such a width that their forward ends will protrude far 85 enough to bend down when they are driven to proper position.

The advantages of my invention will be clear to those skilled in the art. The plates may be cheaply and easily manufactured, 90 either by rolling them with the flanges bent in the desired form and then cold-sawing on the dotted lines of Fig. 4; or by rolling them with the flanges projecting at right angles to the surface and then shearing the 95 sections on the dotted lines and bending down the flanges to the desired shape. There being no bolts or rivets to remove or apply in removing or applying the fastening to the rail, such operations may be done 100 quickly and easily. The bending down of the keys gives a permanent securing means which cannot work loose in the manner of nuts; while the fastening may be easily detached by bending up this end of the key 105 and knocking the key out. The plate may

be secured to the steel tie at the point of manufacture, so that the only loose securing parts are the keys.

Instead of forming a tie-plate with the 5 projecting flanges thereon, these clips or flange-portions may be formed on separate pieces and separately secured to the top of the tie in the same relative position as that shown; in which case the rail might rest 10 upon the top of the tie itself. The method of forming the parts may also be varied, and other variations may be made without departure from my invention.

I claim:—

15 1. In a rail fastening, a tie plate secured to a tie and having an integral lug on its upper surface at each side of the rail, said lugs extending at an angle to the longitudinal axis of the rail and a tapering key 20 driven between each of said lugs and the adjacent edge of the rail base, said lugs having their upper portions extending inwardly over the key seats to provide wedging surfaces for the upper faces of the keys, said 25 keys having their lower inner surfaces out of contact with the top surface of the tie plate; substantially as described.

2. In a rail fastening, the combination 30 with a metal tie, of a lug permanently secured to said tie at each side of the rail, said lugs extending at an angle to the longitudinal axis of the rail, and a tapering key 35 driven between each of said lugs and the adjacent edge of the rail base, said lugs being inclined upwardly and inwardly over the key seats to provide wedging surfaces for the upper faces of the keys, said keys having their inner lower surfaces out of contact with the top surface of the tie; substantially 40 as described.

3. A rail fastening comprising a tie plate 45 having an integral lug on its upper surface on each side of the rail, the lugs extending at an angle to the longitudinal axis of the rail and oppositely facing keys driven 50 between each of said lugs and the adjacent rail base, said lugs having their upper portions inclined inwardly over the key seats to provide wedging surfaces for the upper 55 faces of the keys, the keys contacting with the top face and edges of the rail base to prevent edgewise and vertical movement of the rail and having their lower inner surfaces out of contact with the top surface of the tie; substantially as described.

4. In a rail fastening, the combination 60 with a metal tie, of a lug permanently secured to said tie at each side of the rail, said lugs extending at an angle to the longitudinal axis of the rail, and a tapering key 65 between each of said lugs and the adjacent edge of the rail base, said lugs being inclined upwardly and inwardly over the key seats to provide wedging surfaces for the upper

faces of the keys, the keys contacting with 65 the top faces and edges of the rail base to prevent edgewise and vertical movement of the rail, said keys having their lower inner surfaces out of contact with the top surface of the tie; substantially as described. 70

5. In a rail fastening, a tie plate secured to a tie and having an integral lug on its upper surface at each side of the rail, said lugs extending at oppositely facing angles to the longitudinal axis of the rail and a 75 tapering key driven between each of said lugs and the adjacent edge of the rail base, said lugs having their upper portions inclined upwardly and inwardly over the key sides to provide wedging surfaces for the 80 upper faces of the keys, said keys having their lower inner surfaces out of contact with the top surface of the tie plate; substantially as described.

6. In a rail fastening, the combination 85 with a metal tie, of a lug permanently secured to said tie at each side of the rail, said lugs extending at oppositely facing angles to the longitudinal axis of the rail, and a tapering key 90 between each of said lugs and the adjacent edge of the rail base, said lugs having their upper portions extending upwardly and inwardly over the key seats to provide wedging surfaces for the upper faces of the keys, said keys having their 95 lower inner surfaces out of contact with the top surface of the tie; substantially as described.

7. In a rail fastening, a tie plate arranged 100 to be secured to a tie, said plate having lugs at each side of the rail and spaced apart therefrom, said lugs projecting above the upper faces of the rail base and a tapering key driven between each lug and the adjacent edge of the rail base, said keys having 105 their lower inner surfaces out of contact with the top surface of the tie plate; substantially as described.

8. In a rail fastening, a tie plate arranged 110 to be secured to a tie, said plate having lugs at each side of the rail and spaced apart therefrom, the lugs projecting above the upper faces of the rail base and a tapering key 115 between each lug and the adjacent edge of the rail base, the rail base resting directly upon the body of the tie plate, said keys having their lower inner surfaces out of contact with the body of the tie plate; substantially as described.

9. A rail fastening comprising a tie plate 120 arranged to be secured to a tie having means for insulating the tie plate from the said tie, said tie plate having lugs at each side of the rail projecting upwardly and inwardly above the upper faces of the rail 125 base, and a tapering key engaging with one of said lugs for securing the rail to said tie plate, said key having its lower inner surface

out of contact with the top surface of the tie plate; substantially as described.

10. A rail fastening comprising a tie plate arranged to be secured to a tie having means for insulating the tie plate from said tie, said tie plate having lugs extending at an angle to the longitudinal axis of the rail at each side of the rail, and projecting upwardly and inwardly above the upper surface of the rail base, and tapering keys be-

tween each lug and the adjacent edge of the rail base, said keys having their lower inner surfaces out of contact with the top surface of the tie plate; substantially as described.

In testimony whereof, I have hereunto set 15
my hand.

EDWIN E. SLICK.
